SEALING MACHINE

Merlin A. Sticelber, Kansas City, Mo., assignor of
fifty per cent to William Stoneman, Jr., Kan-
sas City, Mo.

Application July 23, 1934, Serial No. 736,563

10 Claims.

(Cl. 93—2)

This invention relates to sealing machines of the character adapted for combination with wrapping machines wherein a package is sealed through the medium of a hot wax seal that is normally created by passing some of the overlapped portions of the wrapper over heated elements so that melting of the wax takes place, and the primary object of this invention is the provision of that part of the entire wrapping machine assembly which cools the seal, thereby hardening the wax to cause the overlapped portions of the paper to be held tightly together.

One important aim of this invention is to provide effective, durable, and novel means for performing the functions contemplated to the end that a positive and solid seal is made.

A yet further aim of the invention is to combine with a wrapping machine of the aforementioned character, a sealing machine having as a part thereof, a refrigerating apparatus which serves to cool certain parts of the sealing machine in a way that will constantly present cooling elements for the hot seals of the packages passing through the said machine.

Minor objects of this invention will appear during the course of the specification, referring to the accompanying drawing, wherein:

Figure 1 is a top plan view of a sealing machine embodying this invention and combined with a wrapping machine of conventional type.

Fig. 2 is a vertical, cross section through the sealing machine taken on line II—II of Fig. 1.

Fig. 3 is a diagrammatical view illustrating one embodiment of the refrigerating apparatus which is used to cool the sealing machine elements, and,

Fig. 4 is an enlarged, sectional, detailed view of the accumulation chamber forming a part of the continuous cooling coils.

Heretofore wrapping machines have been equipped with many different means for cooling the hot seal. These means include the use of moisteners, blasts of air, and vats of water. All of these forms of coolers are well known, but have not given satisfaction to the extent that a desirable cooling of the seal takes place as rapidly as required by the industry.

This invention provides means for supplying constantly cold and relatively small friction areas for the hot seal and refrigerating apparatus which effectively maintains cooling elements at a temperature that is low enough to act positively even when packages being sealed are passing through the machine at a relatively high rate of speed. When waxed paper is wrapped about the commodity, some of the overlapped portions

of the paper are heated by hot plates 8 which form a part of the conventional type wrapping machine, not here shown. From this wrapping machine the package is fed into the sealing machine which comprises a relatively stationary metal base plate 10 and a pair of opposed, vertical plates 12 that are supported by brackets 14 which, in turn, are mounted upon screw shafts 16 so that when said shafts are turned, the right and left screw threads formed thereon will move the brackets 14 and associated vertical plates 12 toward and from each other over the upper surface of base plate 10.

Vertical plates 12 contact the ends of the wrapped package 18, while the same is moved along base plate 10. It is the intention that the melted wax on the wrapper of package 18 will at once become hardened, thereby to seal the package and to accomplish this end, plates 10 and 12 are uniquely and effectively chilled by refrigeration.

The refrigerating apparatus forming a part of this sealing machine is of the type shown diagrammatically in Fig. 3. The same consists of a compressor 20, which acts to force the refrigerant through the attenuated tubing which is positioned where the heat exchange will be most effective. Pipes 22 form the coils to refrigerate base plate 10 and these pipes are welded directly to the under side of plate 10. Pipes 24 form the coils to refrigerate vertical plates 12 and, likewise, these pipes 24 are rigidly affixed directly to the outer sides of plates 12. As shown in Fig. 2, these pipes are insulated by embedding them in an insulating material 26 which is confined about tubes 22 and 24, as the case may be, by a housing member made of wood or analogous insulating material. In the case of pipes 24, the box-like housing 28 combines with plates 12 to form the complete box wherein pipes 24 are confined. In the case of pipes 22, a similar box-like structure 30 confines pipes 22 so that the refrigerating action upon plate 10 is made positive. Thus when a package 18 is in position and moving along between plates 12 and upon plate 10, there is a frictional engagement which positively insures that a chilling effect will be had.

In some instances the refrigerating effect upon plates 10 and 12 is required to be intense enough to create a coating of ice 32 along the side of 50 the plates contacted by the package, and when such coating is maintained, a most effective and efficient, quick sealing action is afforded.

The length of plates 10 and 12 when using the refrigerating apparatus in accordance with this 55

invention is relatively short and the package being sealed will invariably be secure and will not necessitate re-wrapping as is oftentimes the case where cooling devices of the character hereinbefore mentioned are employed.

5 In order that adjustment might take place, connecting tubes 34 and 36, which join pipes 22 and 24 and, in turn, pipes 24 of one vertical plate with the similar pipe of the opposite vertical plate, respectively, are made flexible.

10 An accumulation chamber in the form of a cylinder 38 interposed in the continuous series of pipes forming the various coils, is located where pipe 40 leads the refrigerant back to compressor 20. Pipe 40 directly connects cylinder 38 and the compressor and this construction insures that a warm and ineffective refrigerant is introduced from the system to the compressor 20 for re-cycling.

15 20 Any suitable refrigerant may be employed and the size of compressor 20 may be altered to suit conditions, and while there is always means for arresting the action of compressor 20 when a predetermined pressure is created, this invention 25 contemplates the use of any type of regulating device which may be actuated by the temperature of plates 10 or 12 to suit conditions.

30 An example of a regulating device mentioned above is in the form of a mercury bulb thermostat 30 having the mercury container thereof clamped to the coils or plates at any suitable place as at 50 and joined to the thermostat by a tube 52. Thermostat 50 causes movement of electrical contact 54 through an expansion and 35 contraction of the mercury in the unit, to and from stationary contact member 56 whereby to start and stop the motor of compressor 20 as the temperature at the mercury bulb varies. When these contacts are closed, the circuit for compressor 20 is closed from line 58 to wire 60, closed contact points 54 and 56, wire 62, compressor 20, wire 64 and thence back to line 68.

40 Having thus described the invention, what is claimed as new and desired to be secured by

45 Letters Patent is:

1. A sealing machine of the character described comprising means for receiving wrapped packages, having hot wax seals, as they are moved along a path of travel; relatively stationary chilling plates frictionally contacting the hot wax seals as the packages are moving along the said path of travel; and means for subjecting the plates to the action of a refrigerant at sufficiently low temperature to maintain a layer of ice thereon, the same comprising coils of pipe affixed to the said plates adapted to receive the refrigerant.

50 2. A sealing machine of the character described comprising means for receiving wrapped packages, having hot wax seals, as they are moved along a path of travel; relatively stationary chilling plates frictionally contacting the hot wax seals as the packages are moving along the said path of travel, and means for subjecting the plates to the action of a refrigerant to constantly

55 chill the same, comprising chambers formed along one side of the plates; means for circulating a refrigerant through said chambers at sufficiently low temperature to maintain a layer of ice on the sealing faces thereof; and means for stopping the flow of refrigerant through said chambers when the temperature of the plates reaches a predetermined point.

60 3. A sealing machine of the character described adapted to receive wrapped packages, having hot wax seals, as they are moved along a path of

travel, comprising a relatively stationary chilling plate in juxtaposition with the hot wax seals as the packages are moving along the said path of travel; a coil contacting said plate; and means for circulating a refrigerant through said coils at sufficiently low temperature to maintain a layer of ice on the sealing face of said plate, said hot wax seals in motion along said plate being in frictional contact with the layer of ice.

65 4. A sealing machine of the character described adapted to receive wrapped packages, having hot wax seals, as they are moved along a path of travel comprising a base plate supporting the said packages; a pair of spaced-apart vertical plates engaging the ends of the packages; coils in contact with one side of each plate respectively; means for circulating a refrigerant through said coils at sufficiently low temperature to maintain a layer of ice on the other side of each plate; and insulating means adjacent the free surface of said coils and the corresponding sides of said plates to confine heat exchange to the said plate and that portion of the coils contacted thereby.

70 5. A sealing machine of the character described adapted to receive wrapped packages, having hot wax seals, as they are moved along a path of travel comprising a coil of pipe adjacent the respective seals; a housing for said coil respectively including a box-like enclosure having a metal plate forming one side thereof and secured to the pipes of the coil, the remaining sides of said enclosure being of heat insulating material, and a filling of fibrous heat insulating substance within the box-like enclosure, between the coil and said remaining sides; and means for supplying a refrigerant to said coil at sufficiently low temperature to maintain a layer of ice on said metal plate in position to engage the hot wax seals.

75 6. A sealing machine of the character described comprising means for receiving wrapped packages, having hot wax seals, as they are moved along a path of travel; a relatively stationary chilling plate in juxtaposition with the hot wax seals as the packages are moving along the said path of travel; and refrigerating means acting upon one side of the plate at sufficiently low temperature to maintain a layer of ice on the other or sealing side of the plate to contact the hot seals as the packages are moving along the plates.

80 7. In combination with a wrapping machine having a plate for cooling the seals of the packages passing through the machine; a pipe coil; a refrigerant in said coil, said coil being in contact with said plate to permit action upon the latter by the refrigerant, said refrigerant being at sufficiently low temperature to maintain a layer of ice on the exposed side of said plate; means for circulating a refrigerant through the coil to maintain a predetermined temperature at the plate; and means governable by the varying temperature of said plate for regulating the flow of refrigerant through said coil.

85 8. In combination with a wrapping machine having adjustable, opposed side plates and a bottom plate for cooling the seals of the packages passing through the machine; a continuous pipe coil; a refrigerant in said coil, said coil having portions thereof affixed to said plates to permit action upon the latter by the refrigerant, said refrigerant being at sufficiently low temperature to maintain a layer of ice on the exposed side of said plates; means for circulating the refrigerant through the coil to maintain a temperature within

- a predetermined range and flexible sections in said coil to permit adjustment of the side plates as refrigerant is passing through the coil.
9. A sealing machine of the character described 5 adapted to receive wrapped packages, having hot wax seals as they are moved along a path of travel, comprising a pair of side plates movable for adjustment transversely to the path of travel of the packages; a stationary base plate beneath 10 the side plates; a continuous coil having sections thereof rigidly affixed to the said respective plates, and flexible sections interconnecting the said affixed sections to permit relative adjustment of the side plates as refrigerant is passing therethrough; and means for supplying a refrigerant 15 to the coil.

10. A sealing machine of the character described adapted to receive wrapped packages, having hot wax seals as they are moved along a path of travel, comprising a pair of side plates movable for adjustment transversely to the path of travel of the packages; a stationary base plate beneath 5 the side plates; a continuous coil having sections thereof rigidly affixed to the said respective plates, and flexible sections interconnecting the said affixed sections to permit adjustment of the 10 plates as refrigerant is passing therethrough; and insulating means partly embedding the coil sections affixed to the said plates.
